WALTER J. DUDLEY, OF BROOKLYN, NEW YORK, ASSIGNOR OF ONE-HALF TO HENRY S. BLACKMORE, OF MOUNT VERNON, NEW YORK.

SAFETY DEVICE FOR FLUID-FUEL OUTLETS.

1,368,707.

Specification of Letters Patent.

Patented Feb. 15, 1921.

Application filed March 22, 1918. Serial No. 223,953.

To all whom it may concern:

Be it known that I, WALTER J. DUDLEY, a citizen of the United States, and resident of the city of New York, in the borough of Brooklyn, county of Kings, and State of New York, have invented certain new and useful Improvements in Safety Devices for Fluid-Fuel Outlets, of which the following is a specification.

10 This invention relates to a safety device for a fuel outlet, irrespective of whether the fuel is used for power or illuminating purposes, but has special reference to a device that may be advantageously used for 15 automatically controlling the outlet of gas or a fluid for illuminating purposes.

In the use of natural or artificial gas for illuminating purposes, as well as commercial purposes, there is always a danger of 20 the gas being accidentally extinguished by a draft, wind, increments of water in the gas conduit, or other means ordinarily beyond the control of mankind, consequently there is danger of asphyxiation, explosion 25 and other accidents, which this invention aims to obviate by an automatic control of the fuel used for illuminating or other purposes.

The safety device includes a member located in proximity to a fuel outlet and containing air or a liquid, susceptible to expansion, by the application of heat, for opening and also closing a valvular member, which regulates or controls the supply of fuel to 35 the outlet.

The safety device also includes a manually actuated and normally closed valvular member in communication with the source of fuel, which after manual actuation, permits of a pilot light being established to affect an expansive element capable of operating a valve controlling the outlet of the fuel.

The invention also includes simple, durable and easily assembled elements by which the above and other results may be obtained, and reference will now be had to the drawing, wherein,

Figure 1 is a vertical sectional view of the safety device in connection with a gas jet, showing the device normally closed shutting off the supply of gas to the jet;

Fig. 2 is a similar view showing the diaphragm actuated valve in an open position admitting gas to the jet;

Fig. 3 is a side elevation of a portion of the safety device, partly broken away and partly in section, illustrating a manually actuated valve adapted to produce a pilot light;

Fig. 4 is a horizontal sectional view taken on the line IV—IV of Fig. 2;

Fig. 5 is an elevation of the complete safety device, and

Figs. 6 and 7 are modifications, showing 65 double action of diaphragm.

Similar numerals of reference indicate corresponding parts in the several views.

In the drawing, the reference numeral 1 denotes a cylindrical casing having the bottom thereof provided with a small port 2, and a depending interiorly screw threaded connection 3 which permits of the casing being screwed on a fuel supply pipe, for instance, a gas pipe 4. The upper end of the 70 casing 1 is provided with a fixed closure plate 5 having a central opening or port 6 and an upstanding exteriorly screw threaded connection 7 for a stepped or gradually reduced jet tube 8. In the upper end of this 75 jet tube is mounted a ported jet or nipple 9 adapted to receive gas or other fuel from the pipe 4 provided there is an unobstructed passage through the casing 1 and the jet tube 8.

Fixed in the closure plate 5 of the casing 1 is a coupling member 22 and this member is tubular so as to communicate with a diaphragm casing 23 having a flexible member diaphragm 24 suitably mounted therein and 85 connected to the member 22, said connection being near the circumference of said diaphragm, so that a change of curvature caused by flexure of the diaphragm causes the casing to pivot on the coupling member 90 instead of advancing and receding as would be the case were the coupling member connected to the center of the diaphragm. The diaphragm casing 23 is cylindrical and has a plate 24^a fixed in the end of the casing 95 after the diaphragm has been assembled therein. The diaphragm casing 23 is adapted to engage a valve member 25 in the form of a plate loosely supported between the casing 23 and the closure plate 5, the engagement being at the edge of the casing diametrically opposite the junction of coupling and diaphragm. The valve member 25 is bifurcated or forked as at 26 to embrace the coupling member 22 and be guided thereby 100

105

110

and as a further guide for said valve member there is a depending pin 27 extending into a slot 28 in the valve member 25. The valve member 25 has a gasket or valve seat member 29 adapted to engage the closure plate 5 and close the port or opening 6 of said plate as shown in Fig. 1 so that the supply of gas or fuel to the jet tube 8 is shut off. Adjacent to the slot 28 of the valve member is a depending hook 30 normally in engagement with the lower edge of the diaphragm casing 23, so that when said casing is lowered or tilted by the flexing of the diaphragm 24 that the valve member 25 is shifted thereby. The hook is merely to insure the dropping of the valve, gravity will usually make it drop.

Communicating with the upper end of the coupling member 22 is a vertically disposed tube or hollow member 31 communicating with a horizontally disposed tubular annulus or ring 32 surrounding and in proximity to the nipple 9 and adapted to be heated, by the flame issuing therefrom. This ring, the coupling member and the diaphragm casing may contain a fluid as air or liquid susceptible to expansion, so that when said ring is subjected to the action of a flame or other source of heat its fluid contents will expand, creating a pressure in the diaphragm casing and flexing the diaphragm which will assume the position shown in Fig. 2, allowing valve plate 25 to fall and establishing communication between the gas supply pipe 4 and nipple 9 and admitting gas to the burner.

The preheating of ring 32 may be made by the flame of an ordinary match, in which case the gas issuing from the nipple will be ignited by the flame of the match and will continue to burn, the heating of ring 32 by the flame maintaining the expansion of the fluid therein and consequently the diaphragm remains flexed and valve 25 open.

If the flame is accidentally extinguished, by a draft or other unforeseen agent, which under ordinary circumstances would eventually permit the gas to escape unignited and undoubtedly result in an accident, the cooling and subsequent contraction of the fluid will result in a reversal of the previously described operation, causing the closure of the valve 25 and cutting off the supply of gas to the burner.

While the burner operates perfectly well using a match as described, I find that it is more convenient to start the burner with the aid of a pilot flame and auxiliary valve for the same and a novel and convenient form thereof has been devised.

The closure plate 5, at one side of the connection 7 has an opening 10 and fixed therein is a tubular valve body 11 projecting into the casing 1 and above the closure

plate 5. In the valve body 11 is a reciprocable valve member 12 provided with a stem 13 extending into the casing 1. The stem 13 has a longitudinal groove 14 which may establish communication between the valve body 11 and said casing and on the lower end of said stem is a valve head 15 and the gasket 16, so that the communication between the valve body and the casing may be shut off when the valvular member 12 is raised. This is accomplished by a coiled compression spring 17 within the valve body 11, and the valvular member 12 has a port or by-path 18 to establish communication between the casing 1 and the atmosphere when the valvular member is depressed.

On the upper end of the valvular member 12 is a horizontally disposed head 19 having one end thereof bifurcated or forked so as to be guided by the jet tube 8. The outer end of the head 19 has a depending rod or member 21 which permits of the valvular member 12 being manually lowered against the action of the spring 17 so that communication will be established between the casing 1 and the valve body 11, thus allowing gas to escape from the valvular member 12 to be ignited and temporarily maintain the pilot light.

Opening 2 is so designed as to admit the quantity of gas necessary for the normal action of the burner which is less than the pressure in the mains, consequently as soon as the gas flame is ignited the pilot flame immediately drops down enough to avoid any overheating of the ring 32—this is important.

Making the connection to one side of the diaphragm is an important feature because by using the change of curvature as the means of utilizing the pressure of the fluid instead of merely the advance or recession of the central part of the diaphragm as hitherto done, a very slight change of curvature in the diaphragm produces a large excursion of the free end of the casing, allowing a smaller diaphragm and of thick material, avoiding danger of permanent set, always the fault of thin diaphragms; also, liquid expansion may be utilized, avoiding excessive pressure of steam generating fluids.

Figs. 6 and 7 show how the motion may be doubled by having a valve lever fixed near the circumference of the diaphragm radially opposite the coupling tube. It is not necessary to have the casing movable in case the latter plan is used, if double action is not desired.

Electric contacts may be made instead of valve operators for fire alarms, or indicating hands for pressure gages or manometers may be operated.

It is thought that the operation and utility of the invention will be apparent.

without further description, and it should be understood that the structural elements are susceptible to such changes as fall within the scope of the appended claims.

5 Having now described my invention what I claim is:

1. The combination with a burner of a tube disposed in proximity to the tip of said burner, a valve for controlling fuel supplied 10 to said burner, a generally flat motive chamber having a normally flexed wall communicating out of a common center thereof with said tube, and adapted to actuate said valve.
- 15 2. The combination with a burner of a tube disposed in proximity to the tip of said burner, a valve for controlling fuel supplied to said burner, a generally flat motive chamber, having a flexible wall and an opposite relatively more rigid wall, suspended 20 from the flexible wall out of a common center by a holding member, and adapted to actuate said valve through a member spaced apart from the supporting member 25 communicating with the chamber wall and the valve, said motive chamber communicating with said tube.
3. The combination with a burner of a tube disposed in proximity to the tip of said burner, a valve for controlling fuel supplied 30 to said burner, a generally flat motive chamber, having a normally flexed wall, suspended from the flexed wall out of a common center by a holding member and containing a thermally 35 expandable and contractible fluid, and communicating at the end thereof with said tube and adapted to actuate said valve.
4. The combination with a burner of a 40 valve, a motive element comprising a chamber having a generally flat form and provided with a flexible wall and with an opposite relatively rigid wall, suspended from the flexible wall out of a common center by 45 a holding member, a thermally expandable and contractible fluid in said chamber, means for conducting heat thereto whereby the pressure in said chamber may be altered, and means communicating with the chamber wall adapted to actuate said valve.
5. The combination with a burner of a 55 valve for closing the gas-passage thereof and a chamber having a generally flat form provided with a flexible wall and a relatively rigid wall, suspended from the flexible wall out of a common center by a holding member containing a thermally expandable and contractible fluid for indirectly actuating said valve and arranged to act when the 60 burner is operating and thereby indirectly maintain the valve in an open position until the burner cools.
6. The combination with a burner of a 65 valve, a fluid containing chamber having a generally flat form and provided with a flex-

ible wall and with an opposite relatively rigid wall, suspended from the flexible wall out of a common center by a holding member, means for conducting heat thereto whereby the pressure in said chamber may 70 be altered, a heat conductor located within thermal conducting proximity to the burner tip and leading to said chamber, and means actuated by the movement of the fluid containing member for controlling said valve. 75

7. A motive element for valves and other purposes, comprising a chamber having a generally flat form and provided with a flexible wall and with a relatively opposite straight wall suspended from the flexible 80 wall out of a common center by a holding member.

8. A motive element for valves and other purposes, comprising a chamber, having a generally flat form and provided with a 85 normally flexed wall and with an opposite relatively rigid wall, suspended from the flexible wall out of a common center by a holding member and containing a thermally expandable and contractible fluid. 90

9. A motive element for valves and other purposes comprising a chamber having a generally flat form and provided with an inwardly flexible curved wall and with an opposite relatively straight wall, supported 95 from the inwardly flexible curved wall out of a common center, and containing a thermally expandable and contractible fluid.

10. A motive element for valves and other purposes, comprising a chamber having a 100 generally flat form and provided with a flexible wall and with an opposite relatively rigid wall, supported from the flexible wall out of a common center, and containing a thermally expandable and contractible fluid. 105

11. In a safety device for controlling the outlet of a fluid, the combination of a normally closed thermally openable feed member having a valve actuating member of generally flat form provided with a flexible wall and with an opposite relatively more rigid wall, supported at the flexible wall out of a common center, with a normally closed manually actuated valvular member adapted to control an initial heating means to 110 primarily effect the actuation and opening of the fuel feed member. 115

12. The combination with a burner having a valve actuating member of generally flat form provided with a flexible wall and with an opposite relatively more rigid wall, supported out of a common center, of normally closed manually actuated pilot igniter. 120

In testimony whereof, I affix my signature in the presence of two witnesses.
